MOP WITH WRINGER ATTACHMENT

Filed Nov. 26, 1928

Harry Hertzberg INVENTOR

BY
Martin Jachimow
HIS ATTORNEY

UNITED STATES PATENT OFFICE

HARRY HERTZBERG, OF BROOKLYN, NEW YORK

MOP WITH WRINGER ATTACHMENT

Application filed November 26, 1928. Serial No. 321,924.

This invention relates to wringing attachments for mops, and its main object is to provide simple means attachable to the handle of any common mop for squeezing the water out of mops of various types.

It is another object of the invention to provide a wringer which can be attached to the handle of any ordinary mop in a few seconds, which does not require the mop to be of any special construction.

It is a further object of the invention to provide a wringer which is applicable to mops of the "knob" or "deck mop" type.

With the foregoing and other objects in view as will appear in the description which follows, the invention resides in the combination and arrangement of parts and in the detail of construction hereinafter described and claimed.

20 In the accompanying drawing forming part of this specification

Fig. 1 shows in a perspective view my wringing attachment in operating position on a deck mop when squeezing water out of 25 the mop.

Fig. 2 shows the wringer attached to the mop stick but removed from the mop while the mop is in use.

Corresponding parts in Figs. 1 and 2 are 30 numbered alike, and these numbers are referred to in the following description.

Referring to Fig. 2 of the drawing, 10 is a 35 mop of the deck-mop type attached to a mop stick 11. Mops of this type consist of a bunch of mop cords of equal length, folded upon themselves at their centers which are tied into a knob suitably connected to the lower end of mop stick 11. Below this knob the mop cords form a tuft of substantially circular cross-section. My wringer attachment 14 is slipped 40 upon stick 11 from its free end. A pin or screw 12 is then inserted into mop stick 11 a suitable distance from its free end. My wringer 14 consists of a single piece of metallic rod which is bent upon itself at its center 45 and then twisted to form a double helix 13. When the wringer is not in use the helical coil 13 is turned to engage pin 12 which holds the wringer in the position of Fig. 2. The two 50 parts of rod 14 which extend from the low-

er end of helix 13 are bent as shown to form the vertical guides 18 and 19 extending lengthwise parallel to mop stick 11. At the extremities of these guides in a plane normal to the mop stick 11, the jaws 15 and 16 are 55 formed. Each jaw consists of two legs which form an angle with each other the apex of which may lean against mop stick 11. The rod of which these legs are made is bent upon itself at the end of each leg for its reinforcement. A ring or hoop 17 is slidably mounted upon the guides 18 and 19 which are bent outwardly towards their lower ends, and as ring 17 is moved downward towards the jaws 15-16, these jaws are pressed closer together, 60 thereby effecting a clamping action for pressing the jaws against mop stick 11. 65

When the wringing attachment is so clamped on the mop stick the mop can be freely and conveniently used for mopping floors 70 and the like.

When the attachment is to be used for wringing the mop, ring 17 is shifted to the upper end of guides 18 and 19 which releases jaws 15-16 from mop stick 11 and they separate to the dotted position of Fig. 2; helical coil 13 is released from pin 12 by twisting wringer 14 on stick 11, jaws 15-16 can then be moved downward and pass over knob 10^b of mop 10 to the neck portion 10^b, when in this position ring 17 is again moved downward on guides 18-19 for clamping the mop material between jaws 15-16. 75 80

As the wringer is also gradually turned on the mop stick and simultaneously shifted towards the lower end of the mop, the mop cords are twisted and the water is effectively removed from the mop. The pressure on the mop 10 is then released by moving hoop 17 85 upward; the jaws 15-16, thus allowed to spread, are moved up over the head of the mop 10 and after diminishing the spread of the jaws again by moving hoop 17 down, the wringer is twisted clockwise around the mop stick 11 until the spiral 13 engages pin 12 and is thereby held in place. 90 95

It will appear clearly from the foregoing description that this wringer is a very useful and efficient device, that it consists of only 100

two parts the construction of which is extremely simple.

It is of particular advantage that the wringer may be applied to any ordinary deck mop, by slipping it over the mop stick and inserting pin 12 without the slightest alteration to the mop itself, and that it may be placed on a new mop when an old one is worn out.

However, while the preferred form of my invention has been described it is to be understood that such modifications may be made in the arrangement of parts and in the construction of minor details as may come within the scope and spirit of the invention as claimed.

What I claim as new and desire to secure by Letters Patent is:

1. The combination with a mop handle of mop material forming a knob and a tuft at the end of said mop handle, wringing means 20 slidably mounted on said handle, comprising a pair of jaws forming together a polygon surrounding said tuft and means for contracting all sides of said polygon towards its center to press against the material of said 25 tuft and for twisting the same.

2. The combination with a mop handle of mop material attached thereto, wringing means slidably mounted on said handle, said means comprising a pair of angular jaws 30 forming together a rectangle to embrace said material for wringing the same and means for moving said angular jaws diagonally of the said rectangle towards the mop axis.

3. The combination with a mop handle and a mop head, of means for wringing said mop head, said means comprising a guide slidably mounted on said handle, a pair of guide rods 40 extending parallel to said handle, a jaw having two legs forming an angle with each other at the lower end of each guide rod and means engaging said guide rods for pressing both legs of each jaw against said mop head to press a plurality of opposite sides of said material towards the mop axis.

4. The combination with a mop and mop stick attached thereto, of a pair of jaws movable towards each other forming a parallelogram around said mop, a pair of guides parallel to said mop stick attached to said jaws, means for sliding said jaws along said mop stick and a ring enclosing said guides for varying the clamping pressure exerted by 55 said jaws by contracting said parallelogram uniformly towards its center.

5. The combination with a mop head, and a handle attached thereto, of a wringer comprising a metallic frame a pair of jaws at the 60 extremities of said frame each jaw being formed to partly surround said mop head and adapted to clamp and to twist said mop material, guiding means for sliding said jaws along said handle, consisting of a plurality of 65 bars holding said jaws at their lower end, and

a helical coil formed integral with said bars at their upper end mounted on said handle.

6. The combination with a mop handle of mop cords joined to the end of said handle forming a tuft thereon of substantially circular cross-section, a frame slidably mounted on said handle, means to guide said frame to slide and rotate on said handle, a pair of jaws at the lower end of said frame bent to completely embrace said tuft, each jaw forming means to press radially different sides of said tuft for gathering said mop cords to the mop axis and for twisting the same.

7. A wringing device adapted to be attached to a mop handle consisting of a single rod of metal bent to form a frame having at its upper end a tubular portion for encircling said handle, a pair of resilient guide rods to extend longitudinally of said handle and a pair of complementary jaws at the lower end of said guide bars straddling said handle in opposite direction, all parts of said frame being formed integral with each other and of said rod, and a ring surrounding said frame for closing said jaws.

Signed at Brooklyn, in the county of Kings and State of New York, this 17th day of November, A. D. 1928.

HARRY HERTZBERG.
